UNITED STATES PATENT OFFICE.

FRED W. MILLER, OF MONROE, WISCONSIN.

PUNCHING AND SHEARING MACHINE.

No. 926,954.

Specification of Letters Patent.

Patented July 6, 1909.

Application filed March 1, 1909. Serial No. 480,539.

To all whom it may concern:

Be it known that I, FRED W. MILLER, a citizen of the United States, residing at Monroe, in the county of Green and State of Wisconsin, have invented a new and useful Punching and Shearing Machine, of which the following is a specification.

This invention relates to a combined metal punching and shearing machine in which a series of different sized punches are provided which are arranged in a circular series on a rotatable disk, and mounted to rotate with said disk is a second disk which is provided with a circular series of dies coöperating with the punches.

The object of the present invention is to provide improved means for mounting and operating the punches, as well as certain novel structural details which will be referred to more fully hereinafter, and also to provide an improved shearing device, and means for operating the same.

With the foregoing objects in view, the invention consists in a novel construction and arrangement of parts to be hereinafter described and claimed, reference being had to the drawing hereto annexed in which—

Figure 1 is a side elevation of the machine. Fig. 2 is a front elevation. Fig. 3 is an enlarged plan view of the punch carrier. Fig. 4 is a side view of the same and the die carrier.

The supporting frame of the machine comprises a pair of cheek plates 5 which are spaced apart a suitable distance as shown in Fig. 2 of the drawing. In the front edges of the cheek plates are recesses 6 which form a space in which the punching mechanism works.

The punching mechanism comprises a disk 7 carrying the punches, and a disk 8 provided with coöperating dies. A plurality of different-sized punches are provided which are arranged in a circular series on the disk 7. Each punch 9 is supported by a carrier 10 which is in the shape of a plunger slidably mounted in openings in the disk 7, the latter being provided with a circular series of such openings. The plunger projects from opposite faces of the disk, and in one of the projecting ends is a socket 11 to receive the punch. The other end of the plunger is formed with a head 12, between which head and the adjacent face of the disk, a spring 13 is coiled around the projecting end of the plunger. In the disk 8 are die openings 14

corresponding in size and shape to that of the punches. The disk 8 turns with the disk 7, so that the particular die corresponding to the punch will always be in alignment with the latter. The two disks are spaced apart a suitable distance by a spacing block 15 therebetween, and they are mounted on a shaft 16 which is mounted in a block 17 secured between the cheek plates 5 adjacent to the recess 6.

Between the cheek plates 5 is slidably mounted a block 18 having at its upper and lower ends forwardly extending portions 19 and 20, respectively, the block being thus shaped similar to the letter C. This block is so located that the under side of its portion 19 extends into the recess 6 above the punch-carriers, and there being an undercut groove 19a in said side extending from one end to the other, to receive the heads 12 of the punch carriers. The rear edge of the block 18 engages anti-friction rollers 21 mounted between the cheek plates. The front edges of the cheek plates 5, are also recessed as indicated at 22, and to one of said plates is bolted or otherwise secured a stationary shear blade 23, said blade projecting into the recess. The movable shear blade is indicated at 24. The last-mentioned blade is bolted or otherwise secured to the under side of the portion 20 of the block 18, said portion extending into the recess 22.

Between the cheek plates 5, at the upper end of the supporting frame is pivoted, as indicated at 25, a lever 26. Near the base of the machine is fulcrumed at 27, a hand-lever 28 which is connected by a link 29 to the lever 26. Between the lever 26, and the upper edge of the block 18, is loosely located a block 30 which transmits the motion of the said lever 26 to the block 18. The block 30 works between the cheek plates 5, and is engaged by the lever 26 close to the fulcrum 25, whereby a powerful leverage is obtained. The block 18 is also connected by rods 31 to the lever 26.

In operation, the disk 7 is turned until the punch which is to be used is connected to the block 18, the head of the punch carrier being placed within the groove 19a. The work to be punched is then placed on the disk 8, and the hand lever 28 is swung downwardly, whereupon through the connections already described, the punch is forced through the work, the die opening in the disk 8 coöperating with the punch in the usual manner.

The thrust of the lever 26 is transmitted to the block 18 through the block 30, there being no thrust on the rods 31, said rods only serving to lift the block 18 when hand lever 5 28 is swung in the opposite direction. Inasmuch as the shear blade 24 is also carried by the block 18, it will be seen that the shear is operated by the same mechanism which operates the punches.

10 By the construction herein described a machine is had which is strong and powerful, and suitable for heavy work. It can be easily operated, and the arrangement of levers is such that sufficient power is obtained 15 to enable the machine to be manually operated.

What is claimed is:

1. In a punching machine, a supporting frame, comprising spaced cheek plates recessed in one of their edges, a block mounted 20 between the plates adjacent to the recess, a shaft rotatably mounted in said block, a pair of spaced disks mounted on said shaft and located in the aforesaid recess, a series of 25 punches carried by one of the disks, and cooperating dies on the other disk, and means for operating the punches.

2. In a shearing machine, a supporting frame comprising spaced cheek plates recessed in one of their edges, a stationary 30 shear blade connected to one of the cheek plates, and projecting into the recess, a movable shear blade, a support for the last mentioned blade mounted between the cheek plates, and operating means connected to 35 said support.

3. In a punching machine, a supporting frame comprising spaced cheek plates, a punch, and means for operating the latter, said means comprising a sliding block mounted 40 between the cheek plates, and having means engageable with the punch to hold the same, a lever pivoted to and working between the cheek plates, and spaced from the block, a connection between the lever and the 45 block, and a block loosely disposed between said lever and the block.

In testimony that I claim the foregoing as my own, I have hereto affixed my signature in the presence of two witnesses.

FRED W. MILLER.
